His attorneys.

UNITED STATES PATENT OFFICE.

CHARLES G. STONE, OF GREENVILLE, PENNSYLVANIA.

DOOR.

Application filed December 22, 1927. Serial No. 241,786.

My invention relates to doors, and particularly to movable door attachments for closing spaces adjacent to the edges of a door.

Difficulty is often experienced in hanging doors so that they may be opened and swung over objects projecting above the door-sill. Large doors on barns, garages and the like are generally mounted to swing outwardly. Such doors are usually carried by hinges secured to one edge thereof, about which the door swings. Accumulations of snow and ice along the outside of such doors frequently result in considerable inconvenience in manipulating them, as the snow or ice accumulates to a depth considerably above the level of the door-sill.

Sometimes a door is placed at the bottom of an incline and it is desired to have the door swing outwardly toward the inclined surface. In such cases it has heretofore been necessary to raise the door-sill considerably above the level of the incline or to provide a substantially flat surface over which the door swings.

I provide a standard door with an auxiliary panel slidably mounted on the door and projecting below the lower surface thereof. Means are provided for raising the auxiliary panel sufficiently to permit it to swing over any obstructions such as snow, ice and irregular or inclined surfaces during the opening movement of the door. Provision is also made for locking the door either in its open or closed position. The auxiliary panel and locking means are attached to any ready-made door and do not require a specially constructed door.

The accompanying drawings illustrate the present preferred embodiment of the invention, in which:

Figure 1 is a face view of a door embodying my invention, in its closed position,

Figure 2 is an inside face view of the door, and

Figure 3 is an edge view thereof.

Referring to the drawings, a door 4 of any one of a large number of ready-made types of doors comprises a frame 5 and a panel 6. The frame 5 comprises upright members 7, cross members 8 and a bracing member 9. The door is secured to a wall 10 by hinges 11 fastened to the upright members 7 and cross members 8 of the frame 5, by any well-known securing means such as screws, nails or the like.

The lower cross member 8 is spaced from a door-sill 12 by an amount sufficient to permit the door to swing clear of any obstructions such as snow, ice, inclined surfaces or the like. For closing the space between the lower cross member 8 and the door-sill 12, I provide an auxiliary panel 14 provided with bracing and guide rods 15. The rods 15 co-operate with securing and guide rods 16 depending from a cross piece 17 attached to the inner surface of the door 4. By this construction the panel 14 is free to move upwardly and downwardly relative to the door 4 between the guides 16.

For moving the panel 14, a handle 18 is pivoted to a surface of the door 4 by a pin 19. The handle 18 is connected to a strap or rod 20 movable longitudinally of the door 4 by a connecting device 21. One example of a connecting device 21 is a lug 22 secured to the strap 20 and provided with a slot 24 in which a pin 25, carried by the handle 18, is seated. The length of the slot 24 is sufficient to permit the handle to be swung from its full line or closed position, shown in Figure 2, to the dotted line position, for raising and lowering the panel 14. The panel 14 is held in its raised or dotted line position by permitting the handle 18 to turn past the center line of the pin 19 until the pin 25 engages the end of slot 24, thereby providing a toggle joint.

The door is locked by a lug 26 projecting downwardly from the panel 14 and engaging a socket 27 formed in the door-sill 12 or in a surface within the radius of the door when in its opened position. The upper end of the strap 20 is secured by a pin 28 to a lever 29 mounted on a pin 30 secured to a cross piece 31 on the inner surface of the door. The upper end of lever 29 is secured by a pin 32 to a latch 34 extending through an eye 35 that is also mounted on the cross piece 31. The latch 34 cooperates with securing means such as an eye 36 mounted on the building.

Assuming the parts to be in the closed position of the door, shown in full lines in Figure 2, and it is desired to open the door, the handle 18 is turned from its lowered or full line position to the upper or dotted line position, thereby raising the auxiliary panel 14 and retracting the latch 34 from the eye 36. The door is then swung about the hinges 11 with the panel 14 in its upper position, thereby permitting the lower edge of the door 4 to clear any obstructions that might

be in its path. At the end of the opening movement, the handle 18 is again turned to its lower position and the panel 14 lowered sufficiently to permit the lug 26 to enter a 5 socket 27 located at any desired point. The door is then held in an open position. For closing the door, the lug 26 is released from the socket 27 by raising the panel 14, the door then being turned on the hinges 11 to 10 its closed position and the panel 14 lowered.

While I have illustrated and described the preferred form of my invention, it will be understood that it may be otherwise embodied within the spirit of the invention and the 15 scope of the following claims.

I claim:

1. In a door structure, a door, an auxiliary panel, an operating handle, and means co-operating with the operating handle for moving the panel longitudinally of the door and locking the panel in either of its extreme 20 positions.

2. In a door structure, a door movable about a vertically extending axis, an auxiliary closing member slidably mounted at 25 one end thereof, locking means for the door capable of occupying a position to be ef-

fective when the door is in its open or closed position, a handle, and means for connecting the handle, locking means and auxiliary closing member for the simultaneous actuation thereof. 30

3. In a door structure, a door movable about a vertically extending axis, an auxiliary closing member movable longitudinally 35 of the door at one end thereof for closing in its closed position a space of variable width between the end of the door and an adjacent structure, and locking means carried by the auxiliary closing member for securing the 40 auxiliary closing member.

4. In a door structure, a door movable about a vertically extending axis, an auxiliary closing member slidably mounted at one end thereof for movement longitudinally 45 of the door, locking means carried by the auxiliary closing member and effective when the door is in a plurality of positions, and means for moving the auxiliary closing member relative to the door and for rendering the 50 locking means effective.

In testimony whereof I have hereunto set my hand.

CHARLES G. STONE.
